UNITED STATES PATENT OFFICE.

CHARLES L. TAYLOR, OF SAN FRANCISCO, CALIFORNIA.

CHECKREIN-LOCK.

1,083,155.

Specification of Letters Patent.

Patented Dec. 30, 1913.

Application filed February 16, 1912. Serial No. 677,982.

To all whom it may concern:

Be it known that I, CHARLES L. TAYLOR, a citizen of the United States, residing at San Francisco, in the county of San Francisco and State of California, have invented new and useful Improvements in Checkrein-Locks, of which the following is a specification.

This invention relates to check rein locks and the object of the invention is to provide a simple and efficient device of this character which may be readily operated so that the horse's head may be released to permit him to drink or graze and may then be checked up without causing the driver to descend from his seat.

Further objects of this invention will appear as the following specific description is read in connection with the accompanying drawing, which forms a part of this application, and in which:—

Figure 1 is a side elevation of the check rein terret. Fig. 2 is an edge elevation of the same applied to the strap with the pawl in the position to hold the strap in its adjusted position. Fig. 3 is a similar view with the pawl arranged to ride idly over the rack bar so that the horse can readily lower his head.

Referring more particularly to the drawing, the terret is provided with a threaded stem 1 having a nut 2 thereon for connecting the head 3 to the saddle. The head 3 comprises an open-work frame having a transverse slot 4 extending therethrough and adapted to receive the check rein strap 5. The end *a* of the strap is adapted to be connected to the ordinary head piece of a check rein and the opposite end *b* is adapted to extend beyond the saddle a sufficient distance to be then reached by the driver. At a suitable point upon the strap, there is secured a raised rack bar 6 preferably in the form of a corrugated sheet of metal, whose

upper edge is raised above the top wall of 45 the slot which passes between the connecting legs of the head, as shown.

Pivots connected between the legs of the head is a freely rotatable pawl 7 whose lower end is substantially flush with the 50 upper wall of the slot when in vertical position and which is adapted to engage the rack bar on either side of the head, as shown in Figs. 2 and 3.

When the pawl is extended to the right 55 side of the head, the horse can not pull the check rein out of the terret but by pulling the strap toward the right, or more correctly speaking, toward the driver until the pawl drops off the rack, it will be readily seen 60 that the strap may move in the opposite direction or toward the horse's head, thus permitting the horse to lower his head for drinking or grazing. After the pawl has passed the opposite end of the strap and the 65 driver pulls upon the strap to check up the horse, the pawl will extend from the head in a proper direction to engage the rack bar for preventing the animal from becoming uncheckered.

70

What is claimed is:—

A check strap lock comprising a guiding terret for a strap, a rack bar arranged to be carried by the strap, and a pendulum pawl 75 freely and pivotally mounted in the terret and having a length between its pivot and its lower end greater than the distance between the pivot and the upper surface of the rack bar when in operative position beneath the terret and less than the distance between 80 the pivot and the lower surface of said rack bar.

In testimony whereof I affix my signature in presence of two witnesses.

CHARLES L. TAYLOR.
